UNITED STATES PATENT OFFICE.

JOHN H. HERBENER, OF NORFOLK, VIRGINIA.

FLAG AND METHOD OF PRODUCING THE SAME.

1,372,508.

Specification of Letters Patent.

Patented Mar. 22, 1921.

Application filed April 10, 1920. Serial No. 372,930.

To all whom it may concern:

Be it known that I, JOHN H. HERBENER, a citizen of the United States, residing at Norfolk, in the county of Norfolk, and State 5 of Virginia, have invented certain new and useful Improvements in Flags and Methods of Producing the Same, of which the following is a specification.

My invention relates to improvements in 10 flags, and to a method of producing the same.

An important object of the invention is to provide simple means for preventing the free end of the flag being torn or injured, in 15 use, thereby prolonging the life of the flag.

A further object of the invention is to provide means for dispensing with the usual hem at the free end of the flag, and leaving this free end raw, such means permitting of 20 a retarded unraveling of such free end, whereby the woof is gradually removed, and the projecting ends of the warp cut or worn, so that the ends of the warp are substantially even, when the next retarding 25 stitch is reached.

A further object of the invention is to provide means of the above mentioned character, which reduces the weight at the free 30 end of the flag, thereby effecting a corresponding reduction in the whipping or cracking action of the flag, when flown in a high wind.

A further object of the invention is to provide a method of constructing a flag of 35 assembled elements of different colors, with retarding stitches of corresponding colors formed upon the elements prior to their assemblage, which method is adapted to simplify and cheapen the production of the 40 flag.

Other objects and advantages of the invention will be apparent during the course of the following description.

In the accompanying drawings forming a 45 part of this specification and in which like numerals are employed to designate like parts throughout the same,

Figure 1 is a side elevation of a flag embodying my invention,

Fig. 2 is a fragmentary side elevation of 50 an unrolled bolt of cloth, showing the method of providing the retarding stitchings, prior to cutting the same into the longitudinal elements or stripes,

Fig. 3 is a side elevation of a plurality of

longitudinal elements or stripes, with the retarding stitches, cut from the unrolled bolt,

Fig. 4 is an enlarged detail section taken on line 4—4 of Fig. 1,

Fig. 5 is a diagrammatic view illustrating the manner of the operation of the retarding stitchings and associated elements, and,

Fig. 6 is a side elevation of a different 65 form of flag embodying my invention.

As is well known, the ordinary flag, such as is used upon a battleship, has its free end provided with a hem, formed by folding the material of the flag upon itself, and stitching the folded portions together. This hem, increases the weight of such free end, whereby the flag tears at or near the line of stitching, when flown in a stiff or high wind. It frequently happens, that the ordinary flag, 75 tears itself in one day, in a strong wind. These flags are ordinarily repaired every few weeks. The hem at the free end of the flag, is provided to prevent raveling of the same, but the added weight of the hem 80 causes the flag to tear, near the stitching of the hem, as above indicated.

I have discovered that the free end of the flag may be left raw, by which is meant that this end is not hemmed or bound, and by 85 the provision of suitable retarding stitching, such free end will unravel very slowly, the woof threads in advance of the next retarding stitching being gradually removed, and the free ends of the warp threads, being 90 gradually and uniformly worn or cut down, whereby the free end is substantially straight, when the next retarding stitching is reached. This retarding stitching retards the unraveling of the woof threads behind 95 it, and is itself removed by the wind, when the warp threads are cut or worn down close to the same. The unraveling or removal of the woof threads in advance of the retarding stitching is greatly retarded due to the 100 fact that the free end of the flag is light, as it has no added weight due to a hem. The absence of this weight dispenses, to a considerable extent, with the cracking or whipping action of the flag, which is one of the 105 principal causes of the hemmed flag being torn, at the stitching.

In the drawings, wherein for the purpose of illustration are shown preferred embodiments of my invention, the numeral 10 110

designates a flag as a whole, which for the purpose of illustration, is a United States flag.

The numeral 12 designates the red stripes, 5 and 13 the white stripes, formed of suitable cloth. These stripes are sewed together by felling or otherwise, as shown at 14 in Fig. 4. The felling consists of arranging the edges of the stripes in interfitting relation, 10 and stitching the same at 15. The numeral 16 designates the blue field of the flag, having the stars 17 sewed therein. This field is secured to the stripes, by sewing or felling, as is well known.

15 My invention resides particularly in the provision of means for preventing the free end of the flag from being torn or injured, when flying in a stiff or high wind, and with this object in view, such free end is left raw, that is to say, it is not hemmed or bound. The free end portion of the flag is provided with a plurality of transverse retarding stitchings 18, sewed upon or within the same. The outermost stitching is suitably spaced from the end of the flag, and the stitchings are spaced from each other, 20 preferably equa-distantly spaced, for one-half to three-fourths of an inch, but this distance and arrangement may be varied, if desired.

It is desirable to have the retarding stitchings of the corresponding or same color as the stripes upon which they are applied. In constructing the flag I have provided a method of forming the stitchings upon the stripes in corresponding colors, which method greatly simplifies and reduces the cost of production. In accordance with this method, I take a bolt or section of cloth 12^a, 30 which would be red for forming the red stripes, and sew or stitch the same transversely, at spaced intervals, depending upon the length of the stripes desired, for providing the sets of spaced retarding stitchings 18. One section of the cloth may now be 35 cut transversely at its left end from the bolt, such line of cutting being suitably spaced from the outermost stitching 18. This section, as clearly shown in Fig. 3, is 40 cut longitudinally into the stripes 12, and these stripes are thereby provided with the stitchings 18, in this instance, the stitchings being red, before the stripes are assembled, and secured together. It is obvious that the 45 white stripes are formed by first transversely stitching the white cloth with white thread, and subsequently cutting the white cloth into the stripes, which are assembled and connected with the red stripes.

50 The invention is in no sense restricted to the use of a flag, the free end of which is formed of a plurality of connected elements or stripes, but may be embodied in a flag, the free end portion of which is formed of 55 a single section of cloth. In Fig. 6 I have

shown a flag formed of a single section of cloth 19, having its free end provided with the retarding stitchings 18, which are continuous throughout its entire width.

The operation of the device may be more 60 readily understood by a consideration of Fig. 5, which may be regarded as showing somewhat diagrammatically the free end portion of the flag, or one stripe thereof. In Fig. 5 the numeral 20 designates the warp threads and 18 the retarding stitchings, while 21 designates the woof threads. It may be assumed that the outermost retarding stitching 18, shown in dotted lines has been removed by the action of the wind, and the successive woof threads similarly removed. As the free end of the flag is freed from the weight of the hem, the whipping or cracking action of such free end, is largely overcome, and the removal of the woof 75 threads 21 will be accomplished very slowly. I have found in actual practice that the woof threads between two of the retarding stitchings 18, which were spaced apart for about one-half an inch, were not entirely 80 removed in a period of three months, within which time the flag was flown in high winds. As the woof threads are thus gradually removed it would seem that the ends of the warp threads would project outwardly 85 beyond the same in the form of an irregular fringe, but this is not the case. There is a short fringe produced as each woof thread is removed, but this fringe is found to be of a substantially uniform length, and the 90 fringe continuously but imperceptibly wears away, and is thus shortened with the removal of the woof threads. The fringe is therefore kept short, and by the time the next retarding stitching is reached, there is 95 only a short fringe 20^a of a substantially uniform length throughout, which is not perceptible when the flag is in use.

It is to be understood that the forms of my invention herewith shown and described 100 are to be taken as preferred examples of the same, and that various changes in the shape, size, and arrangement of parts may be resorted to in the construction of the flag, and that various changes in the order of the 105 steps of the method may be made, and certain steps omitted, without departing from the spirit of my invention, or the scope of the subjoined claims.

Having thus described my invention, I 110 claim:

1. A flag of the character described having its free edge raw and provided near such raw edge with retarding stitching means.

2. A flag of the character described having its free-end raw and provided near such raw end with a plurality of spaced retarding stitchings.

3. A flag having its outer portion formed of a plurality of connected different colored 130

elements, said outer portion having its free end raw, and transverse retarding stitchings formed upon such outer portion, the portions of the stitchings upon each element being of a corresponding color.

4. A flag having its outer portion formed of connected stripes of different colors, each stripe having its free end raw, and spaced transverse retarding stitchings formed upon each stripe near its raw end and being of a corresponding color to that of the stripe.

5. The herein-described method of producing a flag embodying assembled elements of different colors, which consists in forming a plurality of transverse stitches upon a section of cloth of a selected color with the stitches of a corresponding color, then cutting the section longitudinally into elements, and assembling the elements thus produced with other elements.

6. The herein-described method of producing a flag embodying assembled elements of different colors, which consists in forming transverse retarding stitchings upon

each element with the stitchings of a corresponding color to the element, and assembling the elements.

7. The herein-described method of producing a flag embodying assembled elements of different colors, which consists in providing each element at its free end with a raw edge, forming a plurality of retarding stitchings upon each element near its raw edge, such stitchings corresponding in color to that of the element, and assembling and connecting such elements.

8. The herein-described method of producing a flag embodying assembled elements of different colors, which consists in forming stitchings upon a section of cloth of a selected color with the stitching of a corresponding color, cutting the cloth into elements, and assembling the elements thus produced with other elements produced in a similar manner.

In testimony whereof I affix my signature.

JOHN H. HERBENER.
